UNITED STATES PATENT OFFICE.

SAUL ARONSON, OF BROOKLYN, NEW YORK.

PREPAYMENT GAS-METER.

SPECIFICATION forming part of Letters Patent No. 760,721, dated May 24, 1904.

Application filed January 12, 1904. Serial No. 188,722. (No model.)

To all whom it may concern:

Be it known that I, SAUL ARONSON, a citizen of the United States, and a resident of the borough of Brooklyn, in the city and State of New York, have invented a new and useful Improvement in Prepayment Gas-Meters, of which the following is a specification.

This invention relates to improvements in prepayment gas-meters, and has more particularly for its object to provide certain improvements in the delivery mechanism thereof whereby a predetermined amount of gas may be vended, the pressure of the gas being kept up until the supply is shut off instead of the pressure being gradually lessened, as has hitherto been common.

A further object is to provide certain improvements in the construction, form, and arrangement of the several parts of the vending apparatus whereby the same is operated with a small amount of friction, thus rendering it particularly applicable for gas-vending machines.

A practical embodiment of my invention is represented in the accompanying drawings, in which—

Figure 1 represents a portion of a gas-meter in side elevation with my improvement applied thereto. Fig. 2 is a horizontal section through the same. Fig. 3 is a vertical section taken through the vending-apparatus casing, a portion of the gas-inlet and its valve mechanism being shown in section to more clearly indicate the operation of the valve. Fig. 4 is a vertical section through the vending apparatus and casing, taken in the plane of the line A A of Fig. 3. Fig. 5 is an enlarged detail longitudinal central section through the valve-controlling shaft and its adjacent parts, and Fig. 6 is a face view of the cam-gear which controls the opening and closing of the valve.

I have represented in detail herein only so much of the coin-actuated mechanism of the gas-vending machine as will permit a clear understanding of the operation of the vending apparatus itself, the coin-actuated mechanism forming the subject-matter of a companion case filed by me January 16, 1904, its serial number being 189,386.

The gas-meter may be of any well-known

and approved form and is herein denoted by 1. The gas-inlet is denoted by 2, and the outlet by 3.

The usual rotary meter-shaft is denoted by 4, which meter-shaft drives the registering-shaft 5 by its rotary movement, as is common.

The vending-apparatus casing is denoted by 6 and is here shown as attached to the front of the meter 1.

The gas-inlet chamber 7 is provided within 60 the casing 6, which chamber 7 communicates, through a valve 8, with a tube 9, which leads to the meter. This valve 8 is carried by an arm 10, which extends upwardly within the chamber 7 and is locked to a rock-shaft 11, 65 mounted in suitable packed bearings 12 in the front wall of the chamber 7, which shaft 11 is provided exterior to the chamber 7 with a depending arm 13, the free end of which enters a circumferential groove 14 in a sleeve 70 15, fitted to slide longitudinally on the valve-controlling shaft 16. This valve-controlling shaft 16 is mounted in suitable bearings with-in the casing 6 and is driven by the following connection with the meter-shaft 4. A shaft 75 17 is mounted in the top of the meter in suitable bearings, which shaft is provided with a gear 18, which meshes with a worm 19 on the meter-shaft 4. This shaft 17 projects into the casing 6 and is there provided with a 80 worm 20, which meshes with a gear 21, carried by a stud-shaft 22. This stud-shaft 22 is provided with a spur-gear 23, which intermeshes with a spur-gear 24, and a spur-gear 24* in turn intermeshes with a spur-gear 25, 85 fixed to the shaft 16. The speed of rotation imparted to the shaft 16 from the meter-shaft 4 may be adjusted by mounting the spur-gears 24 24* on a stud-axle 26, which is secured in an elongated slot 27, concentric with the axis 90 of the shaft 22, so that the shaft 26 may be clamped at different distances from the shaft 16 to permit a gear 24* of varying sizes to be used.

The sliding sleeve 15 is positively moved in 95 a direction to open or close the valve 8 by the following mechanism: A sleeve 28 is loosely mounted on the shaft 16, which sleeve has fixed thereto a cam-gear 29. The shaft 16 has fixed thereto adjacent to the cam-gear 29 100

a spur-gear 30. The gear 30 is provided with less teeth than the gear 29. In the present instance the gear 30 is provided with fifty-nine teeth and the gear 29 with sixty teeth.

5 A rocking lever is pivoted at 31 to a bracket 32, carried by the gear 30, one arm, 33, of which rocking lever is engaged with a circumferential groove 34 in the sleeve 15 and the other arm, 35, of the lever being engaged 10 with the cam 36 of the cam-gear 29. The connection between the cam 36 and arm 35 is such that the lever is positively rocked in the one or the other direction. An outer sleeve 37 is loosely mounted on the sleeve 28, which 15 sleeve 37 is provided with an arm 38, the free end of which carries a stud axle or pin 39. A pinion 40 is mounted on the stud-axle 39, the teeth of which pinion intermesh with the teeth of the gears 30 and 29. This outer sleeve 37 20 has fixed thereto a gear 41, which is positively driven in one direction by the gear 42 of the coin-actuated mechanism. The coin-actuated mechanism forms no part of this present case, and a description thereof will not 25 be presented herein, it being sufficient to an understanding of the invention that means are provided for positively rotating the sleeve 37 in one direction. As the pinion 40 is rotated around the peripheries of the gears 30 30 and 29 the gear 29 will be slowly rotated and the gear 30 held stationary, because of the geared connection with the meter-shaft, which prevents any movement of the gear 30 except when the valve-controlling shaft 16 is 35 rotated by the rotary movement of the meter-shaft. This movement will cause the cam 36 to slowly travel through the arm 35 of the rocking lever 33 35. The shape of the cam 36 is such that as the gear 29 is started on its 40 rotary movement the rock-lever 35 33 will be moved in a direction to slide the sleeve 15 along the shaft 16, serving to rock the shaft 11 through the arm 13, and thereby open the valve 8, carried by the arm 10. The cam 36 is 45 caused to travel along through the arm 35 of the rocking lever a distance corresponding to the number of rotations of the sleeve 37. The number of these rotations is controlled by the coin-actuated mechanism. After the cam-gear 50 29 has been moved a predetermined distance, determined by the number of rotations of the sleeve 37, the gas-meter shaft 4 will begin to rotate, owing to the opening of the valve 8, thereby rotating the shaft 16. This rotary 55 movement of the shaft 16 will cause the gears 29 and 30 to be rotated. Because the gear 29 is provided with more teeth than the gear 30 the gear 29 will be caused to rotate slower than the gear 30, thus causing the cam 36 to 60 slowly travel through the arm 35 of the rocking lever 35 33 back to its normal position. The cam 36 is caused to travel along through the arm 35 of the rocking lever a distance corresponding to the number of rotations of the 65 sleeve 37. The number of these rotations is

controlled by the coin-actuated mechanism. After the sleeve 37 is rotated the predetermined number of times, according to the coin-actuated mechanism, the gas-meter shaft 4 will begin to rotate, owing to the opening of the valve 8, thereby rotating the shaft 16 in a direction to cause it to return the gears 30 and 29 to their normal position. As before described, the shape of the cam 36 is such that when the gear 29 returns to its normal position the rocking lever 35 33 will be rocked a distance sufficient to close the valve 8 through the sleeve 15 and rock-shaft 11. This will cut off the supply of gas and automatically stop the further movement of the gears 29 and 30. If from any accident there is a leakage of the gas, the construction of the cam 36 is such that the gears 29 and 30 may be continued in their movement, thus preventing the breaking or binding of the mechanism until the leak can be stopped.

For the purpose of indicating the amount of rotary movement imparted to the sleeve 37 the shaft 16 may be provided with a pointer 43 and the sleeve 28 with a dial 44, the dial and pointer being located within the casing 6. Furthermore, the coin-actuated mechanism which is shown herein may be provided with a suitable operating-handle 45, located exterior to the casing 6.

The mechanism which I have described for vending the gas is one which is extremely simple and positive in its action and which may be driven with a small amount of friction. Furthermore, it provides for a device in which different amounts of gas may be vended between very wide margins, the amount varying according to the distance which the gear 29 is caused to travel relative to the gear 30.

While I have described this mechanism in connection with a gas-vending machine, it is to be understood that it is well adapted for use in connection with the vending of any commodity in which a predetermined quantity is to be delivered, controlled by the opening and closing of a valve.

What I claim is—

1. A vending mechanism comprising a valve, a rotary shaft, a sliding sleeve carried by the shaft, a rock-shaft having one arm engaged with the valve and another arm with the sleeve, means under the control of the movement of the rotary shaft for controlling the sliding movement of the sleeve to open and close the valve and means for sliding the sleeve independently of the rotary movement of the shaft.

2. A vending mechanism comprising a valve, a rotary shaft, a sliding sleeve on the shaft for controlling the movements of the valve, a gear fixed to the shaft, a cam-gear loosely mounted on the shaft arranged to travel at a different speed than the first-named gear when the shaft is rotated, a rocking lever carried by the first-named gear engaged

with the sleeve and cam for controlling the movements of the sleeve and thereby the admission-valve.

3. A vending mechanism comprising a valve, a rotary shaft, a valve-controlling sliding sleeve thereon and means for controlling the movement of the sleeve comprising a gear fixed to the shaft, a rocking lever carried thereby, a gear loosely mounted on the shaft, a cam thereon engaging the rocking lever and a common pinion for the two gears, the loose gear having a different number of teeth than the shaft-gear.

4. A vending mechanism comprising a valve, a rotary shaft, a valve-controlling sliding sleeve on the rotary shaft and means for controlling the movement of the sleeve comprising a gear fixed to the shaft, a rocking lever carried thereby, a gear loosely mounted on the shaft and having a different number of teeth than the shaft-gear, a common pinion for the two gears, a rotary arm supporting the pinion, means for rotating the pinion-supporting arm for moving the cam-gear in one direction independently of the shaft-gear, the

said shaft-gear being arranged to drive the cam-gear at a different speed when the rotary shaft is driven by the gas-meter shaft.

5. A vending mechanism comprising a valve, a rotary shaft, a valve-controlling sliding sleeve carried thereby and means for sliding the sleeve to open and close the valve comprising a gear fixed to the shaft, a rocking lever carried thereby engaging the sleeve, a cam-gear loosely mounted on the shaft engaging the lever, said cam-gear having a different number of teeth than the shaft-gear, a common pinion for the two gears, means for controlling its rotary movement bodily around the gears and a dial and pointer controlled by the shaft and cam gears.

In testimony that I claim the foregoing as my invention I have signed my name, in presence of two witnesses, this 9th day of January, 1904.

SAUL ARONSON.
